Attorney

UNITED STATES PATENT OFFICE.

OSCAR BERNHARD HELLSTROM, OF NEUTRAL BAY, NEAR SYDNEY, NEW SOUTH WALES,
AUSTRALIA.

TROUSERS-STRETCHING ATTACHMENT TO CHAIRS.

1,308,755.

Specification of Letters Patent.

Patented July 8, 1919.

Application filed January 31, 1919. Serial No. 274,259.

To all whom it may concern:

Be it known that I, OSCAR BERNHARD HELLSTROM, a subject of the King of Great Britain, residing at Neutral Bay, near Sydney, 5 in the State of New South Wales, Commonwealth of Australia, have invented certain new and useful Improvements in Trousers-Stretching Attachments to Chairs, of which the following is a specification.

10 This invention relates to trousers stretchers which are adapted to be applied to chairs.

The chair is preferably of that pattern known as the "mission" type which is provided with approximately straight cross rails on the chair back and between the rear legs near the bottom. To the rear of the top cross rail are attached two guides or the guides may consist of grooves made in the 15 inner faces of the side members of the back. The body portion of the trousers is laid over the back of the chair and secured by a bar having pins at either end which slide in the guides or grooves. The legs of the trousers 20 hang pendant and on being tightened are secured to the bottom rail by a bar and fastened. Preferably the bottom rail of the chair is made adjustable vertically.

But in order that the invention may be 25 readily understood I now refer to the drawings herewith which illustrate the preferred constructions.

Figure 1 is a perspective view of a chair provided with my attachment, while,

30 Fig. 2 is a partial sectional detail of the upper end of the top rail and guide.

Fig. 3 is a partial view in perspective of a modified form of fastening on the bottom rail.

35 5 is a chair provided with a back having the side members 6—6, a top cross rail 7 and preferably an intermediate rail. 8—8 are brackets secured to the members 6—6 and provided with guiding slots 9—9 in which 40 take the pins 10—10 secured to the clamping bar 11. This bar is adapted to turn on its pins 10 to permit the insertion of the body portion of the trousers and its retention between the bevel face 12 and the top rail 45 which is preferably beveled as at 13.

The lower rail 14 may be fixed but it is 50 preferably adjustable vertically on the teeth or racks 15—15 formed or secured in the inner faces of the legs 16. Adjacent each end 55 of the rail 14 is a pawl 17 which may be re-

silently held in engagement with its rack 15 by a spring. In said rail 14 are also secured, preferably pivotally, two screw bolts 18 which take through slots 19 in the bar 20. On each screw 18 is a tightening wing nut 60 21. The legs of the trousers are firmly clamped between the rail 14 and bar 20 when rail bar 14 carrying with it the bar 20 is forced downwardly as far as possible.

Instead of a loose bar 20 I may have a 65 bar such as 22 pivotally held between the bracket 23 hinged at 24 and the end piece 26. This bar 22 is held in the parallel position by means of the spring catch 25 engaging the end piece 26 but the bar 22 may be 70 turned on its pivots when it is desired to insert or withdraw the trouser legs from between it and the bar 14, or the bar 22 may be swung outwardly on its hinge after releasing the catch 25. 27 are projections or 75 pins on the end piece 26 which take in corresponding holes in the bar 14.

Having thus described my invention, what I claim as new and desire to protect by Letters Patent is:—

80 1. In a chair attachment for stretching trousers, a vertically sliding and pivoted bar adjacent to and parallel with the top rail of the back, and a bar adjacent to and parallel with the bottom rail and adapted to be 85 clamped thereto, the trousers being stretched and held between said rails and their respective bars substantially as described.

2. In a chair attachment for stretching trousers as claimed in claim 1, making the 90 lower rail and its bar adjustable vertically substantially as described and as illustrated.

3. In combination with a chair having a top rail at the back provided with a beveled rear face and a bottom rail, a vertically 95 slidable and pivoted bar adjacent to and parallel with said top rail, said bar being adapted to coact with said beveled rear face to clamp trousers therebetween, and a bar adjacent to and parallel with the bottom 100 rail, said bar being clamped to the bottom rail after the lower end of the trousers have been arranged therebetween.

4. In combination with a chair having a top rail provided with a beveled rear face 105 and a vertically adjustable bottom rail at the back, a vertically slidable and pivoted bar adjacent to and parallel with said top rail, said bar being adapted to coact with said beveled rear face to clamp trousers 110

therebetween, a second bar adjacent to and parallel with the bottom rail, and means for clamping said second bar to the bottom rail to act on the lower end of trousers arranged therebetween.

5. In combination with a chair having a top rail and a bottom rail at the back, a vertically slideable and pivoted bar adjacent to and parallel with the top rail, a second 10 bar hingedly connected at one end to said bottom rail, and means for securing the other end of the bar to said bottom rail.

6. In combination with a chair having a top rail and a bottom rail at the back, a 15 vertically slideable and pivoted bar adjacent to and parallel with the top rail, a second bar hingedly connected at one end to said bottom rail, and pivotally supported means for securing the other end of said bar to 20 said bottom rail.

7. In combination with a chair having a top rail and a bottom rail at the back, a vertically slideable and pivoted bar adjacent to and parallel with said top rail, a second

bar hingedly connected at one end to said 25 bottom rail, and spring impelled means for securing the other end of the bar to said bottom rail.

8. In combination with a chair having a top rail and a vertically adjustable bottom rail at the back, a vertically slideable and pivoted bar adjacent to and parallel with the top rail, a second bar hingedly connected at one end to said bottom rail, and means for securing the other end of the bar to said 30 35 bottom rail.

9. In combination with a chair having a top rail provided with a beveled rear face and a vertically adjustable bottom rail at the back, a vertically slideable and pivoted 40 bar adjacent to and parallel with the top rail, a second bar hingedly connected at one end to said bottom rail, and spring impelled means for securing the other end of said 45 bar to said bottom rail.

In testimony whereof I have hereunto set my hand.

OSCAR BERNHARD HELLSTROM.
